[57] CLAIM

The ornamental design for a binocular with eyecups therefor, substantially as shown and described.

DESCRIPTION

FIG. 1 is a top perspective view of a binocular with eyecups therefor, showing my new design;

FIG. 2 is a top plan view thereof;

FIG. 3 is an elevation as seen in the direction of line 3—3 of FIG. 2;

FIG. 4 is an elevation as seen in the direction of line 4—4 of FIG. 2;

FIG. 5 is an elevation of the objective lens end as seen in the direction of 5—5 of FIG. 2; and

FIG. 6 is a bottom plan view as seen in the direction of line 6—6 of FIG. 3.
